UNITED STATES PATENT OFFICE.

LOUIS H. MEYER, OF LAKE PARK, IOWA.

EXPLOSIVE-ENGINE.

1,266,514.

Specification of Letters Patent. Patented May 14, 1918.

Application filed November 23, 1916. Serial No. 133,006.

To all whom it may concern:

Be it known that I, LOUIS H. MEYER, a citizen of the United States, residing at Lake Park, in the county of Dickinson and State of Iowa, have invented certain new and useful Improvements in Explosive-Engines; and I do hereby declare the following to be a full, clear, and exact description of the invention, such as will enable others skilled in the art to which it appertains to make and use the same:

This invention has for its object to provide an improved explosive engine of the two-cycle type, including a novel pump or compressor mechanism operated directly by the engine shaft and designed to deliver a highly compressed charge of explosive mixture to the engine cylinder.

With this and other objects in view, the invention consists in the novel construction, combination and arrangement of parts as will be hereinafter specifically described, claimed and illustrated in the accompanying drawing, in which:

Fig. 1 represents a horizontal sectional view through the improved explosive engine,

Fig. 2 represents a longitudinal sectional view therethrough in the plane of the axis of the compression cylinder,

Fig. 3 represents a longitudinal sectional view through the engine in the plane of the axis of the engine cylinder, and

Fig. 4 represents an end elevation of the engine and compressor cylinders.

Referring to the drawing in detail, where-in similar reference numerals designate corresponding parts throughout the several views, the numeral 5 indicates a base, upon which is supported a horizontally disposed cylinder 6, having the usual water jacket providing the water chamber 7. A piston 8 is reciprocably mounted in the cylinder 6 and is connected with a piston rod 9, to which is attached a cross head 10, slidably supported in guides 11 positioned upon the base 5. A connecting rod 12 is connected with the cross head 10 and with the crank pin 13 of the crank shaft 14, which latter is supported in suitable bearings mounted upon the base 5 at the end of the latter opposite the cylinder 6. Fly wheels 15 are preferably secured to the crank shaft 14.

A compressor cylinder 16 is formed integral with the engine cylinder 6, and is also provided with a water chamber 17 commu-

nicating with the water chamber of the cylinder 6, whereby the water heated by the engine cylinder during operation of the latter is conducted to the chamber about the compressor cylinder, so as to effectively heat the explosive mixture prior to its admission to the explosion chamber of the engine. A piston 18 is reciprocably mounted in the compressor cylinder 16 and is pivotally connected with a connecting rod 19, which latter is attached at its opposite extremity to a crank pin 20, carried by the engine shaft 14, whereby the compressor is operated during operation of the engine. The crank pin 20 of the compressor is arranged forwardly, with relation to the direction of rotation of the crank shaft 14, of the crank pin 13 of the engine, so that the compression of the explosive charge in the compression cylinder reaches its maximum prior to the termination of the compression stroke of the engine piston 8.

The head of the compression cylinder 16 is formed with an inlet port 21, which is connected with a carburetor, not shown, and the passage of the gaseous fuel to the interior of the cylinder is controlled by an inwardly opening valve 22, which is automatically actuated by the suction created in the cylinder during the receding stroke of the piston 18. The head of the cylinder 16 is also provided with an outlet port communicating with the passage 23, which connects the interior of the cylinder 16 with the interior of the engine cylinder 6, and the passage of the explosive mixture from the interior of the cylinder 16 to the passage 23 is controlled by an inwardly opening valve 23.

The head of the engine cylinder 6 is provided with an exhaust port 24 and the passage of the products of combustion from the explosion chamber of the cylinder 6 through the port 24 is controlled by an inwardly opening exhaust valve 25. The port connecting the passage 23 with the explosion chamber of the engine cylinder 6 is controlled by an inwardly opening inlet valve 26. The valves 25 and 26 are preferably of the spring closed type and are mechanically opened by rocker arms 27 and 32, respectively, the rocker arm 27 being actuated by a cam 29 engaged with a push rod 28, and the rocker arm 32 being actuated by a push rod 29 engaging a cam 30. A pivoted rocker arm 31 is also engaged with the ex-

haust valve 23^a of the compressor cylinder 16 and the rocker arm 31 is engaged with the push rod 29^a, whereby the inlet valve 26 of the cylinder and the exhaust valve 23^a of the compressor cylinder are simultaneously opened.

In operation, the explosive charge is drawn through the inlet passage 21 and into the compressor cylinder 16 during the receding stroke of the piston 18, which, as before stated, travels in advance of the engine piston 8. During the subsequent in-stroke of the piston 18 the inlet valve 22 is automatically closed and the explosive mixture in the cylinder 16 is compressed, and as the piston approaches the limit of its inward movement the valves 23^a and 26 are automatically opened by the cam 30 and push rod 29^a, thus permitting the highly compressed charge to enter the explosion chamber of the cylinder 6 through the passage 23. Subsequent to the admission of the explosive mixture to the interior of the cylinder 6 the valves 23^a and 26 automatically close, and during the continued inward or compression stroke of the engine piston 8 the mixture is compressed to a still higher degree and is finally ignited by a suitable ignition device (not shown). Subsequent to the explosion and expansion of the mixture the exhaust valve 25 is automatically opened by the rocker arm 27, push rod 28 and cam

29 and the products of combustion are conducted from the cylinder through the passage 24.

35

What I claim is:

1. In an explosive engine, an engine cylinder, a compressor cylinder, pistons reciprocably mounted in said cylinders, said cylinders having a passage therein connecting them, valves for controlling the passage of gaseous fuel through said passage, angularly disposed rocker arms engaging said valves, and a push rod engaging the converging terminals of the rocker arms simultaneously actuating said valves.

2. In an explosive engine, an engine cylinder, a compressor cylinder, pistons reciprocably mounted in said cylinders, said cylinders having a passage connecting the interiors thereof, inwardly opening valves arranged in the ends of the cylinders for controlling the passage of gaseous fuel through the passage, a reciprocable push rod, and pivoted rocker arms engaging said valves and arranged to be actuated by the push rod simultaneously opening said valves.

In testimony whereof I affix my signature in presence of two witnesses.

LOUIS H. MEYER.
